[57] CLAIM

The ornamental design for an envelope supply tray for printer, as shown and described.

DESCRIPTION

FIG. 1 is a front elevational view of an envelope supply tray for printer showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a perspective view thereof.

The broken line representation of envelopes and a printer in FIG. 7 is for illustrative purposes only and forms no part of the claimed design.

FIG. 1**FIG. 2****FIG. 3****FIG. 4****FIG. 5***FIG. 6**FIG. 7*
